SILK SCREEN PRINTING MACHINE

George W. Reinke, Park Ridge, Ill., assignor to
Roto-Screen Company, Chicago, Ill., a corpora-
tion of Illinois

Application November 22, 1946, Serial No. 711,510

11 Claims. (Cl. 101—124)

1

This invention relates in general to printing machines and particularly to a silk screen printing machine having novel features to produce a fine quality of reproduction.

There have been a number of attempts in the past to produce a satisfactory silk screen printing machine, but numerous difficulties have arisen. For example, properly registering the paper for feeding to the screen has presented a serious problem with the result that earlier machines have been unable to perform as fine a quality of work as that which could be obtained by the hand printing process. Therefore, when fine quality work was necessary, such as that comparable to a lithographic process, the hand printing was resorted to.

These earlier machines presented other difficulties such as the proper coordination of the various parts, and the screen itself was so located that it could not be easily reached for cleaning both sides thereof.

All of the various disadvantages presented by earlier screen printing machines have been overcome in the invention disclosed herein, and numerous other advantages have resulted therefrom. It is, therefore, one of the principal objects of the present invention to provide a silk screen printing machine which will produce a fine quality of work comparable to that of a lithographic process in full four color process reproduction and which will reproduce up to approximately 133 lines half-tone.

Another object is to provide a machine of the character herein described with novel sheet feeding registering means whereby full four color reproduction may be obtained comparable to that of a lithographic process.

A further object is to provide a novel drive mechanism for a silk screen printing machine for properly coordinating the various steps in the printing process and which will permit proper and accurate registering of the paper.

Still another object is to provide a novel inking fountain arrangement whereby proper ink distribution is obtained in properly timed relation with movement of the screen.

A still further object is to provide novel operating and adjusting mechanism for the squeegee bar whereby multi-color printing may take place and the amount of ink forced through the screen thereby may be controlled.

Another and more specific object of the invention is to provide a novel mounting and actuating means for the screen to facilitate cleaning both sides thereof. The manner of mounting and the adjustability of the screen also being such that the screen frame may be moved for proper registration instead of the register pins, thus permitting paper to be fed to the same point at all times.

2

Other objects and advantages of the invention will become apparent upon reading the following description taken in connection with the accompanying drawings in which:

- 5 Fig. 1 is a side elevational view of the machine;
Fig. 2 is a rear end elevational view;
Fig. 3 is an enlarged sectional view taken substantially along the plane of line 3—3 of Figs. 1 and 4;
10 Fig. 4 is an enlarged vertical longitudinal sectional view through a part of the machine taken substantially along the plane of line 4—4 of Fig. 3 and showing the screen in its uppermost position;
15 Fig. 5 is a sectional view similar to Fig. 4, but showing the screen in its lowermost position;
Fig. 6 is a view similar to Figs. 4 and 5 but showing the parts in a still different position;
Fig. 7 is a side elevational view partly in 20 section of the inking fountain and the ink feed bar;
Fig. 8 is a fragmentary front elevational view of that part of the device shown in Fig. 7;
Fig. 9 is a transverse sectional view taken substantially along the plane of line 9—9 of Fig. 5;
25 Fig. 10 is a front end elevational view partly in section and taken substantially along the plane of line 10—10 of Fig. 11;
Fig. 11 is an enlarged fragmentary side elevational view with certain parts removed to show details and taken substantially along the plane of line 11—11 of Fig. 3;
30 Fig. 12 is a fragmentary longitudinal sectional view taken substantially along the plane of line 12—12 of Fig. 10;
Fig. 13 is a detailed end elevational view of the drive mechanism taken substantially along the plane of line 13—13 of Fig. 1;
35 Fig. 14 is a plan view of the drive mechanism shown in Fig. 13;
Fig. 15 is a vertical sectional view of the drive mechanism taken substantially along the plane of line 15—15 of Fig. 13;
40 Fig. 16 is a fragmentary plan view of the printing drum and sheet gripper assembly;
Fig. 17 is a plan view of the screen and screen frame with parts broken away to show details;
45 Fig. 18 is fragmentary transverse sectional view taken substantially along the plane of line 18—18 of Fig. 17 and including in addition the rack guide;
Fig. 19 is a fragmentary side elevational view of the screen frame shown in Fig. 17;
50 Fig. 20 is a fragmentary sectional view of the screen frame taken substantially along the plane of line 20—20 of Fig. 17; and
55 Fig. 21 is a fragmentary sectional view taken substantially along the plane of line 21—21 of Fig. 20.

The silk screen printing machine disclosed herein comprises in general a main frame on which the various operating mechanism is adapted to be mounted. The silk screen through which the printing is done is located angularly for ease in cleaning and is mounted for reciprocation in suitable guides. Although the angle at which the screen is mounted may vary within wide limits, the preferred angle which has obtained satisfactory results in actual practice is approximately 35° with respect to the horizontal. A squeegee for forcing the ink through the screen is suitably mounted adjacent one side thereof and mechanism is provided for withdrawing the squeegee from the screen during its non-printing stroke and for pressing the squeegee against the screen during the printing stroke thereof. An adjustment is provided for the squeegee whereby the amount of ink forced through the screen may be properly controlled.

Novel drive mechanism is mounted at one end of the main supporting frame for properly driving and coordinating the various steps of the printing process. As stated above, one of the great objections and disadvantages of earlier printing machines of this character has been the inability to properly register the paper so as to obtain a fine quality of work comparable to that of a lithographic process. The drive mechanism of the present invention is such as to permit a proper register of the paper against grippers which carry the paper around a cylinder and against the screen, such grippers being gradually retarded in their rotary movement toward a sheet to be fed thereto and being stopped in their rotary movement momentarily at the time of gripping the paper to enable the paper to thus be placed thereagainst and provide a proper register therefor.

The various advantages of the present invention and the specific mechanism which has been designed to attain the objects enumerated, will become evident upon a more detailed description of the machine. To facilitate an understanding of the construction and operation of the machine, the description thereof has been divided into separate headings as follows:

1. The drive mechanism
2. The screen reciprocating mechanism
3. The inking fountain
4. The squeegee operating and adjusting mechanism
5. The sheet feeding and delivery mechanism
6. The operation of the machine

The machine may be embodied in and supported by a suitable main frame which, in the illustrated form of the invention, may include a pair of spaced supporting frame members 1 located at the bottom of the machine and the upwardly extending supporting members 2 and 3 at the front and rear ends of the machine respectively. The feed table 4 is located at the front of the machine for the purpose of feeding sheets of paper to the printing mechanism, and may be supported by spaced upwardly and angularly extending members 5 secured at the lower ends to the supporting members 1. Vertically extending spaced angle members 6 adjacent the rear of the machine are adapted to support a part of the drive mechanism and may have additional angularly disposed supporting members 7 at the upper part of the machine to thereby provide a sturdy construction. Horizontally disposed spaced apart angle members 8 are located

near the upper part of the machine to which various actuating means may be mounted, and angularly disposed guide members 9 are positioned at each side of the frame to support the screen frame for reciprocation.

The driving mechanism

For the sake of clarity, the end of the machine where the feeding of the paper takes place for the printing operation will be referred to as the front end of the machine, and the rear end thereof will be that end where the printed sheet is delivered. The motive power which actuates the driving mechanism is preferably located at the rear end of the machine and comprises a suitable support 10 on which an electric motor 11 may be mounted. The motor 11 is provided with a suitable shaft 12 to which is secured a pulley 13 adapted to drive a pulley 14 mounted on the shaft 15 (see Fig. 2) by means such as the belt 16.

The shaft 15 is suitably mounted at each end thereof in the bearings 17 and 18, this latter bearing being mounted on the upwardly extending supporting member 19 which is in turn secured to the transversely extending angle member 20 forming a part of the main frame.

Any desirable means may be provided for connecting the main drive shaft 15 to the driving mechanism so that the connection therebetween may be released to stop further operation of the machine. This may be done by a suitable clutch mechanism including a manually operated lever arm 21 secured to a shaft 22 which has a small arm 23 also secured thereto so that actuation of the arm 21 will rotate the shaft and induce a rotary motion of the arm 23. This latter arm is provided with a link 24 pivotally secured at its other end to an upwardly extending arm 25 by means of the pivot pin 26. The arm 25 is bifurcated at its upper end to provide a yoke 27 and is pivotally mounted to the supporting member 19 in such a way that actuation of the arm 21 will move the yoke 27 toward the right or toward the left as viewed in Fig. 2 for actuating the clutch mechanism.

The upper end of the arm 25 is suitably connected to a clutch mechanism 28 to thereby releasably connect the shaft 15 to the shaft 29. This latter shaft is connected to a speed reducer 30 of any suitable and well known construction whereby the shaft 31 thereof will rotate at a reduced speed.

The shaft 31 has mounted thereon the large gear 32 adapted to be in mesh with a smaller gear 33 on the shaft 34 which also has secured thereto the small operating pinion 35 adapted to actuate the drive mechanism for reciprocating the screen frame and properly coordinating the gripper fingers of the sheet delivery mechanism.

Figs. 13, 14 and 15 illustrate the preferred form of driving mechanism and the operation thereof will be made more clear by reference to these figures where the mechanism is shown apart from the other details of the machine as in Fig. 2. The end of the shaft 34 is adapted to be mounted in a roller bearing 36 as shown in Fig. 15. The drive mechanism includes a vertically reciprocating frame comprising the upper and lower bars 37 and 38. A rack frame 39 is adapted to be so mounted on these bars 37 and 38 so as to permit not only a vertical reciprocation of the rack frame, but also a reciprocating

movement from side to side on these bars. The construction is such that the bars are stationary during side to side reciprocation of the rack frame 39 thereon, but will be carried with the rack frame during vertical reciprocation thereof.

Upper and lower supporting bars 40 and 41 may be welded or otherwise secured to the rack frame 39 and are adapted to support the bearings for the rack frame to be mounted on the transverse bars 37 and 38. The mounting means of the upper bar 40 includes a pair of spaced members 42 secured to one end thereof and adapted to support spaced apart roller bearings 43 and 44, one on each edge of the bar 37. The other end of the supporting bar 40 also has secured thereto a pair of similar members 45 having roller bearings 46 and 47 located therebetween also in contact with the upper and lower edges of the bar 47. The lower supporting bar 41 is similarly constructed by being provided at one end thereof with the supporting members 48 having the roller bearings 49 and 50 secured thereto and at its other end the members 51 with the roller bearings 52 and 53 thereon.

The bar 37 at the upper part of the frame is adapted to be received between the upper rollers 43 and 46 and the lower rollers 44 and 47. Likewise, the lower bar 38 of the frame is received between the upper rollers 49 and 52 and the lower rollers 50 and 53. It will thus be evident from this construction that when the rack frame 39 is caused to reciprocate vertically, it will carry with it the upper and lower bars 37 and 38. It will also be clear that the rollers mentioned above provide a bearing surface to permit the rack frame 39 to be moved from side to side on the bars 37 and 38.

The rack frame 39 has mounted at one side thereof a rack 54 which is adapted to be in mesh at all times with the pinion 35 mounted on the shaft 34. The rack 54 is composed of spaced vertically extending rack members 55 and 56 at each side thereof and with horizontally extending rack portions 57 and 58 at the upper and lower ends thereof respectively. The upper and lower rack portions join with the side rack portions 55 and 56 to thus provide a continuous rack of substantially a rectangular shape with rounded corners which will be in mesh at all times with the pinion 35. Since the shaft 34 and pinion 35 mounted thereon are secured to a stationary part of the main frame, a rotation of the pinion 35 will cause a movement of the rack frame 39 in both a horizontal and vertical direction. As the frame moves in a horizontal plane, it will remain stationary with respect to any vertical movement, and during the vertical reciprocation thereof no movement will occur in a horizontal plane except during the period of movement when the pinion 35 is in mesh with the rounded corners of the rack.

This movement of the rack frame 39 and the bars 37 and 38 on which it is mounted may be more easily understood by viewing Fig. 14. Here it will be noted that the two horizontally extending bars 37 and 38 are connected at their ends by means of a vertically extending flange 59 at each end thereof. Each flange 59 is provided with a roller 60 extending in one direction and other rollers 61 positioned at right angles thereto. A guide bar 62 extends vertically adjacent each of the flanges 59 and has a centrally located elongated groove therein adapted to receive the rollers 61. The rollers 60 are adapted

to bear against that portion of each guide 62 located adjacent the central groove therein.

The manner in which the drive mechanism just described actuates the various parts of the machine to coordinate the various steps of the printing operation will become more apparent upon a description of each of the mechanisms separately. For the present it will be sufficient to understand that operation of the motor 11, when the clutch 28 is engaged, will rotate the shaft 34 and the pinion 35 in mesh with the teeth on the rack 54. In the position of the rack shown in Figs. 2 and 13, if the pinion 35 is rotating in a clockwise direction, the rack and its frame 39 will be moving toward the left and the horizontal bars 37 and 38 will remain stationary until the rounded corners of the rack are reached at which time the entire frame will begin to move upwardly. This upward movement continues until the bottom of the rack portion 56 is reached at which time the frame and its connected parts will reach its uppermost position. There will then be a dwell or pause in the vertical movement of the frame while it is moving back toward the right and until the pinion 35 reaches the rack portion 56, at which time the frame will be moved downwardly. This action occurs during operation of the machine continuously and will act to reciprocate the screen frame, will properly apply the ink to the screen and will actuate the grippers at the proper moment while they remain stationary during the above referred to dwell. During this dwell, the grippers will be opened by mechanism to be described hereinafter at which time the paper may be moved thereagainst in proper register and then moved against the screen for the printing step.

The screen reciprocating mechanism

40 In describing the screen and its connection with the rack frame 39 whereby the screen is caused to reciprocate on the main frame, reference will be particularly made to Figs. 1, 3, 4, 5, 6, 7 and 8. A rack 63 is positioned vertically at each side of 45 the moving frame and is secured as by welding or other suitable means to the upper and lower horizontally extending cross bars 37 and 38. Thus, as the bars 37 and 38 are reciprocated in a vertical plane by movement of the rack frame 39, 50 the vertically extending racks 63 will also be caused to reciprocate vertically. A gear 64 is mounted at each side of the main frame and is adapted to rotate freely on the shaft 65. These gears 64 have a rotary reciprocating motion which 55 is transmitted thereto by being in mesh with the racks 63. As these racks reciprocate vertically, a rotary reciprocation of the gears 64 will occur.

A screen frame 66 having a printing screen 67 60 mounted thereon is located below the gears 64 and are mounted for a reciprocating movement in the angularly disposed side frame members 9. Each side of the screen frame 66 is provided with a rack 68 on the upper side thereof adapted to also 65 be in mesh with the gears 64, whereby a rotary reciprocating movement of the gears 64 will cause a reciprocation of the screen and screen frame in an angular direction as more clearly seen in Figs. 4, 5 and 6. A counter-balancing spring 70 69 is suitably secured to each of the gears 64 at one end thereof and to a stationary part of the main frame at the other end thereof to aid in the operation of the various reciprocating parts whereby less power is necessary to operate the machine.

The novel construction of the screen frame whereby the screen may be adjustably mounted therein may be more clearly understood by reference to Figs. 17 through 21 inclusive. Here it will be seen that the screen frame at each side thereof is provided with a side member 70 to which the upper rack 68 is secured along one edge thereof and a lower rack 71 is secured adjacent the bottom edge thereof. The screen frame is adapted to ride in guide members consisting of spaced guide bars 72 and 73 secured to the inner side of the angularly extending side frame members 9. The two guide bars 72 and 73 being mounted in spaced relation will thus provide an elongated groove 74. The frame itself has a pair of rollers 75 mounted on the underside of the rack 68 and a second pair of rollers 76 suitably mounted adjacent the lower rack 71 which extend within the space 74 to provide support for the screen frame during reciprocation thereof. The rollers 75 at each side of the screen frame are adapted to ride on the guide bars 72, maintaining perfect sidewise alignment, and the rollers 76 are mounted at substantially right angles with respect thereto and ride on the guide bars 73.

The screen itself is mounted on an angle iron frame 77 on which may be mounted floating wooden frame members extending along the four sides of the screen. The lower angle member 78 is adapted to rest on a second angle member 79 which has secured thereto a pair of clamping members 80. Each clamping member is provided with a screw threaded clamp 81 so that as the screen frame is inserted at the lower end thereof between the angle member 79 and the clamping members 80, the members 81 may be utilized to clamp the screen in place.

A novel feature of this machine is the provision of a fine adjustment for the screen within the screen frame whereby the position of the screen therein may be adjusted for purposes of proper registry. When the screen is thus adjusted, it will permit a sheet of paper to be fed into the machine at the same point each time. It never becomes necessary to change the position of any gauge pins or other registering devices against which the edge of a sheet of paper being fed into the machine is to be placed. The adjustable feature of the screen and its frame is more clearly illustrated in Figs. 17, 20 and 21 where it will be noted that the upper horizontal edge of the screen frame is provided with an inner angle member 82 and an outer angle member 83. These angle members are so positioned relative to each other that one leg of each member is in contact with each other and the other legs thereof extend upwardly in substantial parallelism. The upwardly extending leg of the angle member 83 is provided with a T-slot 84 adapted to receive the threaded end of an adjusting nut 85. The threaded end thereof is received by a threaded opening in a block 86 secured to the angle member 82. The other leg of the angle member 83 has a slot 87 therein adapted to receive a clamping nut 88 which extends through the opening 87 and is secured to the angle member 82. Thus it will be evident that by screwing the adjusting member 85 in one direction or the other, a corresponding movement of the angle bar 82 will be effected. As may be seen in Fig. 5, the upper edge of the screen frame 77 is adapted to abut against the angle member 82 so that as the clamping members 81 are loosened slightly as well as the clamp member 88, an adjustment of the screen may be had by means of the adjusting member 85. When the

screen is in proper registry, the clamps 81 and 88 may be tightened and the screen will be ready for the printing operation.

When the rack frame 39 is caused to reciprocate vertically carrying with it the racks 63, the two gears 64 in mesh therewith will have a rotary reciprocating movement. Likewise, the screen and screen frame within which it is mounted, having suitable racks 68 also in mesh with the gears 64, will be caused to reciprocate in an angular direction through the guide bars 72 and 73. A novel inking fountain and means for distributing the ink over the screen in preparation for the printing operation is located at the lower end of the screen frame and will now be described.

The inking fountain

The lower end of the screen frame is provided with a forwardly and upwardly extending ink retaining member 90 as may be seen in Figs. 4, 7 and 8, whereby a fountain is provided extending the width of the screen at the lower end thereof within which a quantity of ink 90 may be provided at all times and may be moving with the screen during the reciprocation thereof.

The ink is caused to be distributed over a portion of the screen at the lower side thereof by means of a movable framework consisting of an upper transversely extending rod 91 having a roller 92 at each side thereof adapted to be rolled against the upper guide bars 72 as the screen moves upwardly. A lower transversely extending rod 93 is connected with the rod 91 by means of the connecting bars 94 at each end thereof. Each of the racks 68 has an extension 95 at the upper end thereof adapted to have secured thereto a carrying member 96 which may take any suitable form and, in the illustrated embodiment of the invention, may comprise merely a block of metal. A stop member 97 is adapted to be welded or otherwise suitably secured to the side frame members 8 and 9 at the juncture thereof and against which the rollers 92 will bear to support the rods 91 and 93 after the screen frame has moved downwardly a sufficient distance.

In the operation of the ink distributor, when the screen frame moves upwardly, the lower rod 93 will be immersed in the ink 90 as shown in Fig. 4. The frame consisting of the rods 91 and 93 will be carried upwardly by the carrier members 96 for the full distance of the screen movement, but on the downward movement thereof, the rollers 92 will come against the stop members 97 and withdraw the lower rod 93 from the ink 90 as the screen continues to move downwardly, at which time the relative position of these parts will be like that shown in Fig. 7. As the rod is withdrawn from the ink, it will carry with it a quantity of the ink and distribute it over the lower part of the frame. On the next upward movement of the screen, the ink thus distributed will be carried with the screen, but as it moves downwardly again the ink will be picked up by the squeegee and forced through the open interstices of the screen and transferred to a sheet of paper on the opposite side thereof for printing. The printing operation and the construction of the squeegee will now be described.

The squeegee operating and adjusting mechanism

Reference will now be made more particularly to Figs. 3, 4, 5, 6 and 9 where the flexible squeegee is indicated by the numeral 98. The squeegee is suitably mounted on a bar 99 extending trans-

versely of the screen and screen frame and may be of any suitable length. That is to say, if the printing impression is to take place throughout the entire width of the screen, then the squeegee and its mounting bar 99 may extend the full width thereof. On the other hand, if the subject matter to be printed is to consume a relatively small or narrow area on the screen, then the squeegee and its supporting bar may be of a width just sufficient to cover the printing area. This type of construction is also advantageous for simultaneous multi-color printing whereby the inking fountain may be provided with partitions with a different colored ink in each section thereof and a plurality of squeegees may be mounted so that each will print with a different colored ink.

One or more of the squeegee bars 99 may be clamped in place on a mounting member 100 which extends throughout the width of the screen. Any suitable clamping or mounting means can be utilized for securing the squeegee in place, and the illustrated form includes a clamping member 101 having a block 102 adapted to be placed against the bar or mounting means 100 and a second smaller block 103 adapted to bear against the squeegee bar 99. Suitable bolts may then be inserted through the member 101 and the blocks 102 and 103 to thereby clamp the squeegee bar 99 in place. This construction is clearly illustrated in Figs. 4, 5 and 6.

It is necessary that the squeegee 98 be held forcibly against the screen during the printing operation to transfer the ink therethrough to the paper on the opposite side thereof. It is equally necessary that the squeegee be removed from the screen during the non-printing reciprocating movement thereof. To accomplish this result I have provided novel mechanism for pressing the squeegee against the screen during the downward movement thereof and for elevating the squeegee away from the screen during the upward movement thereof. This mechanism comprises a plate 104 at each side of the screen frame to which the supporting member 100 is secured. Each plate 104 is mounted on an extension 105 of a bar 106 which extends downwardly at each side of the machine and is mounted for a rotary movement on the transversely extending shaft 107 suitably mounted in bearings 108. The bearings 108 are located on a transversely extending stationary angle member 109 of the main frame to which the counter-balancing spring 69 may also be secured as shown. The upper ends of the extensions 105 are secured together by means of the transversely extending bar 110.

An adjusting bar 111 is also located at each side of the machine and is mounted for pivotal movement on the bars 106 by suitable pivot pins 112. The upper end of each adjusting bar 111 is bifurcated as indicated at 113 and is adapted to be received within the sides of a U-shaped bracket 114 mounted on the connecting bar 110. An adjusting screw 115 threadedly engages each of the brackets 114 whereby it may extend between the sides thereof, each screw 115 being provided with an annular groove 116 adjacent its inner end to receive the bifurcated end 113 of the bar 111. This construction admits of a suitable adjustment to be made with respect to the pressure of the squeegee 98 against the screen during the printing operation. This adjustment may become necessary because of different circumstances such, for example, as where the viscosity of the ink

may vary thus requiring more or less pressure to force it through the interstices of the screen.

The actuating means for raising and lowering the squeegee is secured directly to each of the 5 adjusting bars 111 and moves the squeegee the same distance upon each operation thereof. Thus the force with which the squeegee bears against the screen will depend upon the initial location of the adjusting bars 111 with respect thereto. 10 If the adjusting screws 115 are moved outwardly from the brackets 114, the bars 111 will be elevated so that when the actuating mechanism moves the squeegee against the screen, it will bear against it with a lesser force. Likewise, if 15 a greater force is desired, then the adjusting screws 115 may be moved inwardly whereby the adjusting bars 111 will be closer to the screen.

Additional clamping means in the form of a member 117 at each side of the machine and secured to the cross bar 110 is provided which has an elongated clamping bolt 118 threadedly secured thereto. The outer end of this bolt is adapted to bear against the clamping means 101 for the squeegee supporting bar whereby the entire structure is securely held in place.

The actuating means for moving the squeegee toward and away from the printing screen consists of a slide member 119 at each side of the machine having an elongated recess 120 therein 30 adapted to receive the shaft 65. One end of the slide 119 is secured to the adjusting bar 111 as at 121 whereby a reciprocating movement of the slide member 119 will carry with it the bar 111 and the squeegee connected thereto through the 35 means described above. The sliding movement of the slide member takes place about the shaft 65.

A shaft or rod 122 extends transversely of the machine and is secured at each end thereof to a slide member 119. Two other transversely extending rods 123 and 124 are also mounted on the slide members 119 at the opposite end thereof. The rod 122 has a cam follower 125 rotatably mounted at each end thereof and similar cam followers 126 are located at each end of the rod 123, 40 while the cam followers 127 are mounted at each end of the rod 124. An actuating cam 128 is secured to the shaft 65 at each end thereof by any suitable means such as the clamping member 129 whereby the cam will be rotated continuously 45 in the same direction with the shaft 65. The means by which this shaft rotates will be explained hereinafter.

Between the ends of the shaft 65 and the various rods above mentioned, a limiting bracket is 55 located which is provided with spaced side members 130 adapted to embrace the shaft 65 and which has at one end thereof a spacer member 131 and at its other end a slotted bracket 132. The rod 122 is adapted to be received by the slot 60 in the member 132 and limits the reciprocating movement of the slide member 119.

The shaft 65 is mounted in suitable bearings 133 and 134 secured to the supporting side frame members 8 of the main frame. One end of the 65 shaft 65 has a bevel gear 135 secured thereto and is adapted to be in mesh with another bevel gear 136 mounted on the shaft 137 which extends along one side of the machine from the front to the rear thereof. At the rear end of the machine, the shaft 137 is mounted for rotation in a bearing 138 and has a toothed wheel 139 secured thereto adjacent the rear end. A chain drive 140 is in engagement with the toothed wheel 139 and also engages a small toothed wheel 141 on the 70 shaft 31. The chain then passes over an idler 75

wheel 142 and as the shaft 31 is the driving shaft emanating from the speed reducer, it will thus drive the shaft 137 by means of the chain 140. Obviously, rotation of the shaft 137 and the bevel gear 136 thereon in mesh with the bevel gear 135 will rotate the shaft 65 to which is secured the cams 128. In the position of the cam 128 as shown in Fig. 4, the edge thereof is bearing downwardly against the rollers 125 of the slide member 119. When this occurs, the slide member and the parts connected thereto, including the adjusting bars 111, the bars 106 and the squeegee 98 will also be moved downwardly so that the squeegee will exert a pressure against the printing screen. This driving means is so synchronized with respect to the reciprocating movement of the screen and screen frame as to actuate the squeegee 98 toward and against the screen as the screen moves downwardly. When the screen reaches its lowermost position, or before such time if so desired, the cam 128 will be rotated to its position shown in Fig. 5 where the edge thereof bears against the rollers 127 and elevates the slide members 119 together with the squeegee connected thereto. As the cam continues to rotate, the edge thereof will also contact the rollers 126 to maintain the squeegee in its elevated position during the upward movement of the screen.

As explained above, during the upward stroke of the screen, the lower cross member 93 of the inking frame will be immersed in the ink 90, so that as the screen moves downwardly to its lowermost position, the inking frame will distribute a quantity of ink across the bottom portion of the screen. The ink will thus remain in this position until the screen again reaches its uppermost position, at which time the cam 128 is operated to press the squeegee against the screen and the ink which has been distributed thereon, so that such ink will be forced through the screen and onto a sheet of paper at the opposite side thereof for the printing operation as the screen moves downwardly.

The sheet feeding and delivery mechanism

The sheet of paper to be printed may either be fed by hand to the machine or any suitable form of automatic sheet feeding means may be used. In the illustrated form of the invention, no automatic sheet feeding means have been disclosed, but the manner in which the sheet is gripped and rolled against the screen for printing will be the same even though the sheets are fed by hand. The sheets may be manually placed on the feeding table 4 and fed to a drum 144 located beneath the screen and which has a gear 145 at each side thereof mounted for rotation on the transversely extending shaft 146. These various parts may be more clearly understood by viewing Figs. 3, 4, 5, 10, 12 and 16.

These gears 145 are adapted to be in mesh with the racks 71 on the underside of the screen frame so that as the screen reciprocates, the drum will also have a rotary reciprocating movement. The drum is provided with an opening 147 extending substantially throughout the length thereof against one edge of which suitable gripper fingers may be actuated to grasp the edge of a sheet of paper being fed thereto and roll it against the screen. A number of strengthening webs or spacers 148 may also be disposed in spaced relation throughout the length of the drum if so desired.

The gripper finger assembly comprises a supporting bar 149 extending substantially the 75

length of the drum and mounted along one edge of the opening 147. A plurality of gripper fingers 150 are adapted to be reciprocated in such a way that when they are in closed position, they will bear against an edge of the supporting bar 149 and when in open position they will be adapted to receive the edge of a sheet of paper. Each gripper 150 has an inwardly extending tail piece 151 slidably mounted within a block 152 on the supporting bar 149. The tail piece 151 has a projection 153 thereon against which a rotary reciprocating actuator 154 is adapted to bear for actuating the gripper finger 150 and moving it to its open position to receive a sheet of paper. The actuator 154 is suitably secured on the rock shaft 155 whereupon a rocking of the shaft in one direction will urge the gripper outwardly away from the drum and a movement in the opposite direction will permit the coiled tension spring 156 secured thereto to draw the gripper inwardly by reason of the connection of the other end of the spring to a rod 157 extending lengthwise of the drum. Any suitable number of gripper assemblies may be located in spaced relation on the supporting bar 149 and along the shaft 155 so that a sufficient number may grasp the edge of a sheet and roll the sheet against the underside of the screen in its downwardly movement.

Suitable mechanism is provided for rocking the shaft 155 each time the drum 144 reaches the end of its rotary reciprocating movement in both directions. Fig. 4 shows one of the grippers in its closed position for gripping the edge of a sheet of paper for printing and Fig. 12 shows the gripper in its open position with the shaft 155 rotated a sufficient amount for the actuating member 154 to move the gripper 150 outwardly. It is just as necessary to open the grippers at or before the end of their rotary reciprocating movement in the opposite direction so that the printed sheet may be delivered from the machine. The actuating mechanism for rocking the shaft 155 may be more clearly understood by reference to Figs. 10 and 11 where it will be noted that the rock shaft 155 is mounted for rotation with the drum 144 and extends beyond the drum whereby a cross member 158 may be keyed thereto. This cross member 158 rotatably supports the cam followers 159 and 160 at each end thereof. A suitably mounted cam 161 is so located that when the rotation of the drum is in a counter-clockwise direction and the grippers thereof are in the position shown in Figs. 4 and 12, the cam 161 will be in a position relative to the cam roller 159 as shown in Fig. 11. At this moment, suitable mechanism to be described hereinafter, will elevate the cam 161 against the cam follower 159 which will thus impart a rocking movement of the shaft 155 in a clockwise direction. By reference to Figs. 4 and 12, it will be obvious that such a rocking of the shaft 155 will cause the gripper fingers 150 to be moved to open position in readiness for receiving the edge of a sheet of paper.

A second cam 162 is mounted on an upwardly extending support 163 secured to the horizontal stationary support 164 at the opposite side of the drum 144, whereby, when the drum is rotated in a clockwise direction, the cam roller 160 will come against the undercurved side of the cam 162 and again rotate the rock shaft 155 in a clockwise direction to open the gripper fingers 150 and permit the printed sheet being held thereby to be delivered from the machine.

The shaft 146 supporting the drum 144 is suit-

ably mounted in bearings 165 also located on and secured to the horizontally extending stationary frame member 164.

When paper is fed to the machine along the table 4, it is necessary that adjustable side guide members be provided to compensate for different widths of paper even though the machine has been designed to permit a feeding of the paper to the same point at all times. One form which the side guide or stop member may take is illustrated in Fig. 3 where the stop member 166 is shown as being secured to a slidably mounted bar 167 mounted for a sliding movement within the guide members 168 and 169. The outer end of the bar may be provided with a plurality of spaced apart openings 170 adapted to receive a pin 171 extending between the sides of the guide 169. In this way, the pin 171 may be removed and the bar 167 together with the stop member 166 thereon may be moved in either direction to a location suitable for the size of the sheet of paper being fed, and the pin then replaced in a suitable opening 170 which will hold the side stop in its proper position. It will be evident that any other suitable form of side stop as well as securing or clamping means therefor may be used if so desired.

As the paper is being fed to the grippers 150 it is desirable that a plurality of guide fingers be provided for guiding the edge of the sheet downwardly and to prevent the edge from curling upwardly. To this end a transversely extending supporting bar 172 spaced upwardly from the table 4 is provided which has a plurality of guide fingers 173 curved downwardly and extending toward the drum. The fingers 173 terminate short of the position of the gripper fingers 150 in sheet receiving position so that no interference with the operation of the grippers will result.

A plurality of movable gauge or register pins are also provided to enable the operator of the machine to initially position the paper properly for feeding to the grippers. As the operator feeds the sheet toward the drum, the forward edge thereof will first come against a plurality of these pins for a preliminary positioning of the sheet. When the gripper fingers open and are in readiness to receive the sheet, then the pins move upwardly. The cylinder gripper fingers then slightly bump against the sheet assuring registration on the cylinder itself. To the attainment of this end, a transversely extending pin supporting bar 174 is provided having a plurality of spaced apart gauge pins 175 extending downwardly therefrom and positioned closely adjacent the drum 144. Each end of the bar 174 is rounded so that it may be rotatably mounted within a supporting member 176 located at each side of the machine. The bar 174 is caused to rock by means of an extension 177 secured to one end thereof, which extension is adapted to be received between the legs of a U-shaped bracket 178 (see Fig. 10). Suitable securing means are provided to fasten the end of the member 177 within this bracket and, as will be presently pointed out, a vertical reciprocation of the bracket 178 will carry the end of the member 177 with it and thus cause a rocking movement of the bar 174 to raise and lower the gauge pins 175.

The bracket 178 is secured to one of a pair of spaced supporting plates 179 which, in turn, are each secured at their inner ends to a vertically reciprocating bar 180. This bar 180 is guided in its vertical movement by the bracket 181 and has at its upper end a transverse extension 182 adapted to receive an adjusting screw 183. The

screw 183 may be adjusted upwardly or downwardly to adjust the downward movement of the bar 180 and its connected parts since it bears against the upper end of the bracket 181 in its lowermost position.

Referring again to Fig. 11, it will be clear that the lower end of the reciprocating bar 180 is pivotally connected to a link 184 having a slot 185 in its outer end adapted to receive a suitable pin 186 for purposes of guiding the movement of the link. The cam 161 above referred to as actuating the rock shaft 155, is mounted on the link 184 and is movable therewith. It will thus be clear that an upward movement of the reciprocating bar 180 will perform two functions, one of which is to carry with it the bracket 177 for rocking the bar 174 in a clockwise direction for operating the gauge pins 175, and the other of which is to elevate the cam 161 to rock the shaft 155 also in a clockwise direction to open the gripper fingers 150.

The actuating mechanism for reciprocating the bar 180 and its connected parts consists of a pair of spaced apart plates 187 secured to the plates 179 and which are adapted to support between their outer ends a cam follower 188. A cam 189 of a suitable configuration is keyed to the shaft 137 which is journaled in its forward end by a bearing 190 secured to the upwardly extending supporting member 191 of the angle member 164. As the cam 189 rotates, it will contact the cam roller 188 and elevate the parts connected therewith which include the reciprocating bar 180 and the rock shaft 155 as well as the rocker bar 174. When the lower part of the cam 189 is reached, the various parts will drop downwardly by gravity which will actuate the gauge pins 175 and the gripper fingers 150 in the opposite direction. The drive means for rotating the shaft 137 have been described above and the cam 189 is so positioned thereon as to actuate these various parts in timed relation so as to grasp the sheet and roll it against the underside of the screen in properly timed relation with the reciprocation thereof.

A delivery mechanism for delivering the printed sheet from the machine is also provided. It will be understood that any suitable form of mechanism may be utilized for this purpose, the means disclosed herein being merely for purposes of illustration. The delivery means disclosed may be more readily understood by reference to Figs. 12 and 16 where a gripper device generally indicated at 192 is mounted on a chain driving means 193 located at each side of the machine and immediately below the drum 144. The chain 193 is driven by means of a toothed wheel 194 mounted at each end of a transversely extending shaft 195 at the forward end of the machine and another toothed wheel 196 at each side of the machine located rearwardly thereof. The shaft 195 is mounted for rotation in suitable bearings 197 located at the forward end of the main supporting frame and the toothed wheels 196 are mounted for rotation on a transversely extending shaft 198 which has a bevel gear 199 mounted at one end thereof.

The chains 193 and the gripper devices 192 are caused to move continuously in a counter-clockwise direction as indicated in Fig. 12 by means of a bevel gear 200 in mesh with the bevel gear 199, which gear 200 is mounted on a rearwardly extending shaft 201 journaled in bearings 202 and 203 mounted at the front and rear ends of the frame respectively.

Referring momentarily to Fig. 2 it will be ap-

parent that the shaft 201 has a toothed wheel 204 thereon which is driven by a chain 205 in engagement at its upper end with a toothed wheel 206 mounted on the shaft 137. The driving means for the shaft 137 has been explained above and it will thus be clear that rotation of the shaft 137 through the chain drive will continuously rotate the shaft 201 and shaft 198 for moving the gripper devices 192.

This mechanism is so synchronized with the rotary reciprocating movement of the gripper fingers 150 that when the grippers 150 reach their position as shown in Fig. 5, they will have released the forward edge of the printed sheet at which time the gripper devices 192 will have been moved to a position adjacent thereto and will be actuated to grasp the sheet and carry it downwardly for deposit on suitable delivery belts whereupon the printed sheet will be delivered from the machine.

Each gripper device 192 may have a construction as illustrated in Figs. 12 and 16 where a supporting plate 207 is mounted on the inner side of each of the chains 193. The mounting of this plate on the chains may preferably be by means of the rods 208 which are secured at their ends to the chains 193. A rock shaft 209 is mounted for rotation at each end thereof in the end members 210 each of which carries a cam roller 211. A plurality of spaced apart gripper fingers 212 are also secured to the rock shaft 209 which will be caused to open and close upon a proper rocking of the shaft 209. The gripper fingers 212 each have mounted adjacent thereto a bar 213 mounted on the rods 208 and each of which has a transversely extending projection 214 immediately below the gripper end of each of the fingers 212. The bars 213 are stationary and the gripper fingers 212 are normally in contact with the projections 214 for gripping, but may be moved away therefrom for purposes of receiving the edges of the printed sheet when the shaft 209 is rocked in the proper direction. A torsion spring 215 is suitably mounted on the shaft 209 for normally maintaining it in a direction for closing the gripper fingers 212.

The shaft 209 is caused to rock for purposes of opening the gripper fingers 212 at two points in their travel, one for grasping the edge of the sheet and carrying it away from the drum 144 and the other for dropping the sheet and depositing it on the delivery belts. This mechanism includes a cam plate 216 located at each side of the machine and which is mounted on an upwardly extending supporting bar 217 suitably secured to the transversely extending angle member 218 on the main supporting frame. The lower end of the bar 217 is angularly disposed as at 219. Thus it will be evident that as the gripper devices 192 move upwardly adjacent the drum 144, the rollers 211 mounted thereon will bear against the edge of the cam plates 216 which will cause a rocking of the shaft 209 and an opening of the gripper fingers 212. At this point, the gripper fingers 150 on the drum 144 will have released their grip on the printed sheet and will permit the gripper devices 192 to pick up the sheet and carry it around and downwardly for deposit on the delivery belts. As the gripper devices 192 approach the position as shown in Fig. 12, the rollers 211 will bear against the under edge 219 of the bars 217 and again rock the shaft 209 for opening the gripper fingers 212, whereupon the printed sheet will be dropped downwardly.

The delivery belts 220 (see Fig. 1) extend throughout the length of the machine and rear-

wardly thereof and are caused to move in a rearward direction by passing around the transversely extending shaft 221 at the rear of the machine. This shaft 221 is rotated by means of a toothed wheel 222 mounted thereon which has a chain 223 in mesh therewith and also with another toothed wheel 224 mounted on the shaft 225 suitably mounted in the bearings 226 and 227. A gear 228 is secured to the shaft 225 and is caused to rotate by being in mesh with the pinion 229 on the shaft 29. It will therefore be clear that as long as the clutch 28 is in engagement for driving the shaft 29, the belts 220 will operate to carry away the printed sheets deposited thereon by means of the gripper devices 192.

As is customary in machines of this character, an air line 230 is suitably located at the front of the machine and is caused to aid the printed sheet as it is being carried around by the chains 193. This practice is well known and need not be further described at this time.

The mechanism disclosed herein is capable of printing on various sizes of paper sheets and in actual practice it has been found that excellent results have been obtained by printing on sheets up to 44 by 64 inches. The sheets may be fed mechanically or manually along the table 4 toward the drum 144 and against the gauge pins 175. Assuming that the machine is operating continuously and the screen 67 has been adjusted in its frame for proper registry, the drive mechanism illustrated in Fig. 2 including the pinion 35, will be caused to reciprocate the rack frame 39 in both a horizontal and vertical direction. Starting from the position of the various parts as shown in Fig. 2, where the rack frame 39 is in its lowermost position, the racks 63 will also be in their lowermost position and the screen frame will be in its uppermost position with the ink delivery bar 93 immersed in the ink 90 in the fountain 89. Also in this position the drum 144 carrying the gripper fingers 150 will be in substantially the position shown in Fig. 12. At this point, the gauge pins 175 against which the forward edge of the sheet is resting will be caused to move upwardly by a rocking of the bar 174 through the mechanism illustrated in Fig. 11. Also the gripper fingers 150 will be in their opened position by reason of the rocking of the shaft 155 in a clockwise direction through the actuation of the cam 161 against the cam follower 159. Immediately thereafter the pinion 35, which is rotating in a clockwise direction, will be moving the rack frame 39 toward the left as viewed in Fig. 2. It should be pointed out that during the dwell where no vertical movement of the rack frame 39 is taking place, the drum 144 with its gripper fingers 150 will remain stationary, giving the sheet a light nudge backward when moving at relatively slow speed and giving sufficient time for the grippers to close before resumption of motion in the opposite direction. Thus, the sheet is actually registered on the cylinder itself. This construction is designed to overcome the objection to earlier machines which cause such gripper fingers to close with a sliding motion or while in motion, making registry uncertain and variable. In such machines there has been no means for retarding or slowing down the approach of the gripper fingers as they reach the forward edge of the sheet of paper. The present construction will permit such a retarding of the movement of the gripper fingers 150 at the time the pinion 35 is in contact with the rounded corners of the rack on the frame 39.

As the rack frame 39 continues to move toward the left and the pinion 35 moves around the upper righthand corner thereof, the racks 63 begin an upward movement which causes a rotation of the gears 64 and a downward movement of the screen and screen frame. This movement will also close the gripper fingers 150 against the forward edge of the sheet to carry the sheet against the underside of the screen. The cam 128 will also be moved to its position as shown in Fig. 4 for urging the squeegee 98 against the screen and as the screen continues to move downwardly the squeegee will force the ink which has been previously delivered to the screen onto the paper therethrough. This action then continues until the rack frame 39 reaches its uppermost position whereupon the screen will be in its lowermost position and the drum 144 carrying the gripper fingers 150 will be in the position as shown in Fig. 5.

At this point the printing operation will be completed and the gripper fingers 150 will be again opened by movement of the cam follower 160 against the cam 162 for releasing the printed sheet and permitting the gripper assemblies 192 to pick up the sheet and carry it downwardly to the delivery belts 220.

This construction allows printing to take place at a uniform speed throughout, because the retarding and dwell takes place after the printing operation has been completed. Thus, the disadvantage of earlier machines in obtaining an uneven distribution of ink, is not present here.

From the foregoing description it will be apparent that novel improvements have been made in the silk screen printing art whereby excellent results and a fine quality of printing have been obtained. Proper registry is always assured because of the retarding of the rotary movement of the gripper fingers and their complete stoppage during the time that a sheet of paper is being taken by them. Furthermore, the novel form of distributing the ink on the screen is such as to enable the distribution and printing of several different colored inks simultaneously if so desired, this being also due to the construction of the squeegee bar in sections. The angular position of the screen greatly facilitates the cleaning thereof. It is inevitable that dust or lint collects on the screen and clings to both sides thereof thus necessitating the cleaning of both sides of the screen. This angular disposition of the screen enables the operator to reach both sides thereof with ease and this has been one of the great disadvantages of earlier machines.

It will be evident that changes may be made in the form, construction and arrangement of parts from those disclosed herein without in any way departing from the spirit of the invention or sacrificing any of the attendant advantages hereof, provided, however, that such changes fall within the scope of the claims appended hereto.

Having thus described my invention, what I claim as new and desire to secure by Letters Patent of the United States is:

1. In a printing machine of the class described, a main frame, a screen mounted for reciprocation on said main frame, an inking fountain located adjacent one end of said screen and movable therewith, ink distributing means for distributing a quantity of ink from said fountain onto said screen, means for rolling a sheet of paper against one side of said screen during the printing operation, a squeegee for picking up the ink distributed by said ink distributing means

and forcing it through the open interstices of said screen onto said sheet during reciprocation of said screen in one direction, and driving means for actuating said screen, ink distributing means, and sheet rolling means in timed relation with each other.

2. In a printing machine of the class described, a main frame, an angularly disposed screen and screen frame mounted for reciprocation on said main frame, an inking fountain mounted on the lower end of said screen frame and movable therewith, ink distributing means adapted to distribute a quantity of ink from said fountain onto said screen at the end of each downward movement thereof, means for rolling a sheet of paper against one side of said screen during the printing operation, a squeegee for picking up the distributed ink at the end of the upward movement of said screen and forcing it through the open interstices of said screen on the downward movement thereof onto said sheet, and driving means for actuating said screen, ink distributing means, and sheet rolling means in timed relation with each other.

3. In a printing machine of the class described, a main frame, an angularly disposed screen mounted for reciprocation on said main frame, an ink reservoir, ink distributing means in said reservoir, means to actuate said ink distributing means at the end of a movement of said screen in a downward direction for distributing a quantity of ink onto the lower end of said screen, means for rolling a sheet of paper against one side of said screen during the printing operation, a squeegee adjacent said screen mounted for movement away from said screen during reciprocation thereof in one direction and against said screen during reciprocation thereof in the other direction for picking up the distributed ink and forcing it through the open interstices of said screen onto said sheet for printing, and driving means for actuating said screen, sheet rolling means, and squeegee in timed relation with each other.

4. In a printing machine of the class described, a main frame, a screen and screen frame mounted for reciprocation on said main frame, means for rolling a sheet of paper against one side of said screen during the printing operation, an inking fountain located adjacent one end of said screen and movable therewith, ink distributing means for distributing a quantity of ink from said fountain onto said screen, means for transferring the distributed ink to said sheet through the open interstices of said screen during reciprocation thereof in one direction, drive means for actuating said screen and screen frame and the rolling means in timed relation with each other, and means for adjusting the position of said screen within said screen frame to obtain proper registry and thereby permit the sheets to be fed to the same point at all times.

5. In a printing machine of the class described, a main frame, an angularly disposed screen and screen frame mounted for reciprocation on said main frame, means for rolling a sheet of paper against one side of said screen during the printing operation, an inking fountain located adjacent one end of said screen and movable therewith, ink distributing means for distributing a quantity of ink from said fountain onto said screen, means for transferring the distributed ink to said sheet through the open interstices of said screen during reciprocation thereof in one direction, drive means for actuating said screen and screen frame

75

and the rolling means in timed relation with each other, and means for adjusting the position of said screen within said screen frame to obtain proper registry and thereby permit the sheets to be fed to the same point at all times.

6. In a printing machine of the class described, a main frame, an angularly disposed screen frame mounted for reciprocation on said main frame, a printing screen adjustably mounted within said screen frame and reciprocable therewith, means for rolling a sheet of paper against one side of said screen during the printing operation, an inking fountain located adjacent one end of said screen and movable therewith, ink distributing means for distributing a quantity of ink from said fountain onto said screen, means for transferring the distributed ink to said sheet through the open interstices of said screen during reciprocation thereof in one direction, drive means for actuating the screen and screen frame and the rolling means in timed relation with each other, and means for finely adjusting the position of said screen within said screen frame to obtain proper registry and thereby permit the sheets to be fed to the same point at all times.

7. In a printing machine of the class described, a main frame, a screen mounted for reciprocation on said main frame, an inking fountain located adjacent one end of said screen and movable therewith, ink distributing means for distributing a quantity of ink from said fountain onto said screen, means for rolling a sheet of paper against one side of said screen during the printing operation, means for transferring the distributed ink through said screen and onto said paper during reciprocation of said screen in one direction, and driving means for actuating said screen, ink distributing means and sheet rolling means in timed relation with each other.

8. In a printing machine of the class described having a reciprocating printing screen therein, a rotary reciprocating cylinder, and grippers on the cylinder adapted to grip a sheet of paper and roll the sheet against said screen for printing, drive means for reciprocating said screen and cylinder comprising an actuator including a rack and rack frame mounted for multi-directional movement, a reciprocable supporting frame, said actuator being mounted on said supporting frame for movement therewith and with respect thereto, rack and pinion means connecting said supporting frame with said cylinder, and means to move said actuator, whereby movement thereof in one direction with said supporting frame will rotate said cylinder and grippers toward the edge of a sheet to be gripped thereby, and movement thereof in another direction with respect to said supporting frame will cause a dwell of said cylinder and grippers while a sheet is being gripped thereby.

9. In a printing machine of the class described having a reciprocating printing screen therein, a rotary reciprocating cylinder, and grippers on the cylinder adapted to grip a sheet of paper and roll the sheet against said screen for printing, drive means for reciprocating said screen and cylinder comprising an actuator including a rack and rack frame mounted for movement in horizontal and vertical planes, a vertically reciprocable supporting frame, said actuator being mounted on said supporting frame for movement therewith in a vertical plane and with respect thereto in a horizontal plane, means for moving said actuator in both of said vertical and horizontal planes.

zontal planes, and rack and pinion means connecting said supporting frame with said cylinder, whereby movement of said actuator and supporting frame in one direction in a vertical plane will rotate said cylinder and grippers toward the edge of a sheet to be gripped thereby, and movement of said actuator in a horizontal plane with respect to said supporting frame will cause a dwell of said cylinder and grippers while a sheet is being gripped thereby.

10. In a printing machine of the class described having a reciprocating printing screen therein, a rotary reciprocating cylinder, and grippers on the cylinder adapted to grip a sheet of paper and roll the sheet against said screen for printing, drive means for reciprocating said screen and cylinder comprising an actuator including a rack and rack frame mounted for multi-directional movement, a reciprocable supporting frame, said actuator being mounted on said supporting frame for movement therewith and with respect thereto, rack and pinion means connecting said supporting frame with said cylinder, means to move said actuator, whereby movement thereof in one direction with said supporting frame will rotate said cylinder and grippers toward the edge of a sheet to be gripped thereby, and movement thereof in another direction with respect to said supporting frame will cause a dwell of said cylinder and grippers while a sheet is being gripped thereby, and means to open said grippers to receive a sheet during the dwell of said cylinder and to close said grippers during rotation thereof.

11. In a printing machine of the class described having a reciprocating printing screen therein, a rotary reciprocating cylinder, and grippers on the cylinder adapted to grip a sheet of paper and roll the sheet against said screen for printing, drive means for reciprocating said screen and cylinder comprising an actuator including a rack and rack frame mounted for movement in horizontal and vertical planes, a vertical reciprocable supporting frame, said actuator being mounted on said supporting frame for movement therewith in a vertical plane and with respect thereto in a horizontal plane, means for moving said actuator in both of said vertical and horizontal planes, rack and pinion means connecting said supporting frame with said cylinder, whereby movement of said actuator and supporting frame in one direction in a vertical plane will rotate said cylinder and grippers toward the edge of a sheet to be gripped thereby, and movement of said actuator in a horizontal plane with respect to said supporting frame will cause a dwell of said cylinder and grippers while a sheet is being gripped thereby, and means to open said grippers to receive a sheet during the dwell of said cylinder and to close said grippers during rotation thereof.
